United States Patent Office

Des. 193,254
Patented July 17, 1962

193,254

BOTTLE RACK

Paul S. Klein, Los Angeles, Calif., assignor to "42"
Products Ltd., Inc., Santa Monica, Calif., a corporation of California

Filed Jan. 29, 1962, Ser. No. 68,554

Term of patent 14 years

(Cl. D58—26)

FIG. 1.

FIG. 2.

FIG. 3.

I claim:

The ornamental design for a bottle rack as shown and described.
